CLARKE F. DAVIS, OF WESTFIELD, AND EDWARD R. SAUNDERS, OF CRANFORD, NEW JERSEY, ASSIGNEES TO STRUCTURAL GYPSUM CORPORATION, OF LINDEN, NEW JERSEY, A CORPORATION OF DELAWARE

BUILDING CONSTRUCTION AND HANGER USED THEREIN

Application filed July 5, 1929. Serial No. 375,926.

This present invention relates to a hanger for use in a building construction in which precast slabs of plastic material such as gypsum or the like, are suspended below beams or purlins, the hanger serving as the connection between the beam, or purlin, and the slab.

The patent to Williams No. 1,547,249, discloses a ceiling construction in which precast slabs having longitudinal reinforcements therein, are suspended below a floor beam or purlin by means secured to the top of the beam, this hanger means being secured to a device embedded in the slab which engages the reinforcement therein.

The patent to Rowan No. 1,632,453, discloses a building construction in which a plurality of precast slabs are suspended from a single hanger supported from the top of the beam, this hanger projecting within a recess in one of the blocks and engaging there the extended ends of reinforcements from adjacent blocks.

It is among the objects of this present invention to provide a hanger and a building construction which will be an improvement upon the constructions shown and described in the above patents, and which will permit the slabs to be suspended from below the top of a floor beam or purlin. Such a construction has a number of advantages over those shown in the above patents, among which is that, when using the same floor beams to support a floor composed of precast slabs, the floor slabs may rest perfectly flat upon the tops of the beams, as no part of the present hanger engages the top surface of the beam.

To this end the invention contemplates hanger means of various forms, adapted to engage a beam or purlin below the top thereof for suspending a ceiling below the beam by engagement with a reinforcement within the slabs forming the same building construc-

tion embodying the hangers, the beams and the slabs.

In carrying out the invention in one of its aspects, a hanger is provided formed either of wire or of strap material one end of which is deformed to penetrate the web of a girder and engage the same, the opposite end extending below the bottom of the girder and having a loop or aperture adapted to receive the ends of metallic reinforcements within the slabs, whereby the slabs are suspended below the bottom of the beam. According to the invention two slabs may be suspended from a single hanger or each slab may have its own hanger, as circumstances shall dictate.

In another aspect the invention contemplates the provision of a single wire or strap hanger passing completely through the web of a beam or girder, and engaging a reinforcement within a slab located on each side of the girder.

In the preferred and the modified forms the slabs may be suspended so that the tops thereof are substantially flush with the under surface of the beam where this is desired, or they may be hung so as to provide a material space between the top of the slabs and the bottom of the beams for the passage of pipes, wires, or the like.

In the drawings:

Fig. 1 is a perspective view of a preferred embodiment of the invention.

Fig. 2 is a sectional view showing the invention in use.

Fig. 3 is a view along the line 3—3 of Fig. 2.

Fig. 4 is a view along the line 4—4 of Fig. 2.

Fig. 5 is a view similar to Fig. 3 showing the hanger in another position on the beam.

Fig. 6 is a view similar to Fig. 2 showing a modified method of hanging the slabs.

Fig. 7 is a view similar to Fig. 2 showing individual hangers for each slab.

Fig. 8 is a perspective view of a modified form of the preferred embodiment.

Fig. 9 is a view of another form of the invention.

5 Fig. 10 is a sectional view showing the device of Fig. 9 in use.

Referring to the embodiment shown in Fig. 1, this consists of a length of wire or round stock 1 bent back upon itself to form a 10 loop 2, the two ends being deformed at right angles to the main body to form feet 3.

In use, and as shown in Figs. 2 and 3, a beam is provided having an aperture in its web, and such a beam may conveniently con- 15

sist of a pair of L irons 4 at top and bottom thereof, enclosing between the pairs a rod or bar 5 arranged in Z formation, that portion of the Z enclosed between the pairs of L irons 4 being pressure-welded throughout as at 6.

20 While this type of beam has been found convenient, yet obviously any girder or purlin may be provided in which an aperture is located in the web to receive the hanger.

The hanger of Fig. 1 is so positioned on the 25 beam that it penetrates the web thereof, the feet 3 engaging the upright portion of one of the L irons 4, and the loop 2 of the hanger extending below the bottom flange of the beam a sufficient distance to engage the projecting ends 7 of longitudinal reinforcements 8 embedded in precast slabs 9. As shown in Fig. 4, these reinforcements project within a recess 10 in each slab and beyond the extreme end of each slab, so that when the two 35 slabs are positioned with their ends adjacent, a portion of the reinforcement of each slab projects within a single recess, where it may be readily grasped by the hanger 1.

Obviously, the hanger 1 may be located 40 either as in Fig. 3 to straddle the bar 5, or between the reaches of the bar, as shown in Fig. 5. In either position the slabs may be so located by proportioning the length of the hanger 1, that the tops of the slabs are substantially flush with the bottom of the beam.

Where it is desired to suspend the slabs well below the bottom of the beam, a longer hanger 11 may be used, as shown in Fig. 6, the arrangement being otherwise substantially the same.

50 Where it is not found expedient to provide a slab or slabs in which the reinforcements therein project entirely beyond the end of the slab, the combination shown in Fig. 7 may be used. Here each slab 9 is provided with a reinforcement 12, the ends 13 of which project within its recess 10 but not beyond the end of the slab. By using two 55 hangers 1, the end 13 of the reinforcement 12 within each slab may be grasped so that the slabs are suspended below the bottom of the beam as before.

In a great many instances it will be found possible to substitute the hanger shown in Fig. 8 for that of Fig. 1. This hanger con-

sists of a metallic strap 14 having a deformed foot 15 and an aperture 16 in the opposite end. Its use is substantially similar to that of the hanger of Fig. 1, although the hanger of Fig. 1 is preferred as against that of Fig. 8, by reason of the fact that it is not always possible to so position the slabs with relation to the beam or girder that the hanger will miss one of the Z rods 5, where a beam of the type shown in Fig. 3 is used. However, as this circumstance will occur but infrequently it is entirely possible to use the strap hanger in practically all places where the wire hanger might be used.

70 In Fig. 9 still another form of hanger is shown which consists of a length of wire or round stock 17 having a loop 18 formed at each end thereof by twisting the wire or the like upon itself, and by arranging this hanger as shown in Fig. 10, the projecting ends 13 of reinforcements 12 within the slots in adjacent ends of slabs 9 may be grasped and both slabs suspended below the beam. Obviously the hanger of Fig. 9 may be also made 75 from a length of strap material, apertured 80 at each end.

In all cases the invention contemplates the filling of the recess or recesses in the ends of the slabs with grouting which embeds the projecting end of the reinforcement and the hanger therein. This not only serves to protect the hanger from fire but likewise produces a substantially monolithic ceiling construction.

85 It will be apparent that in a single building construction any or all of the various forms of hanger combinations herein shown and described may be used, as in some parts of the building it may be desirable to suspend the slabs from I beams, in others from channel beams and in still other portions from a beam having an open web such as shown in Fig. 3. Again, where the bottoms of all beams from which slabs are to be suspended are not on the same level, a ceiling 90 having a uniformly flat under-surface may still be provided by utilizing a combination of hangers such as shown in Figs. 2 and 6.

95 It may be found necessary to provide a plurality of hangers for each end of each slab, depending entirely upon the size and weight of the slab, and in such event the reinforcing rods and hangers may be multiplied as desired to suspend the slab from any 100 number of points.

105 While Fig. 4 shows the recesses within which the projecting ends of the reinforcements are located to consist of isolated depressions, yet obviously these depressions 110 may take the form of a channel or rabbet 125 extending the entire width of the end of each slab, in which event the grouting will be flowed into the recess or rabbet to completely close the same after erection to form a substantially monolithic structure.

The gauge or dimensions of the hanger or hangers will obviously be determined by the weight of slabs to be suspended thereon, but, as ordinarily, no weight rests upon these 5 hangers except that of the slabs themselves and possibly the occasional weight of a workman during erection, the hanger need not be made of unnecessarily heavy material.

In placing the slabs in position to form a 10 floor it will only be necessary to place the hanger in the desired location and then lift the individual slab into position, so that the end of the reinforcement therein passes through the loop or aperture in the hanger 15 as the case may be. The adjacent slab may likewise be positioned either on this same hanger or upon its individual hanger as shown.

It will be apparent that the above hanger 20 and its method of use provides a simple and expeditious manner of suspending slabs from below the top of a floor beam while leaving the upper surface of the beam perfectly flat and without parts projecting thereabove to 25 interfere with the floor to be laid directly thereon. The ceiling itself has a uniformly flat undersurface and is produced without requiring subsequent adjustment and without the necessity of providing forms or the 30 like.

The fact that the entire under-surface of each slab consists of an unbroken mass of gypsum or the like, is highly desirable, in that it forms a fireproof protection not only 35 to the beams and girders, but also to the reinforcements in the slabs and to the hangers engaging the same.

The beams or girders shown may be either those usually occurring in a building structure 40 or specially provided and spaced to take the length of slabs used.

What we claim is:

1. The combination with a fabricated beam having a pair of lower longitudinal truss 45 elements and an open web, a precast slab of plastic material below the truss elements, said precast slab having a reinforcement therein, a portion of which is exposed, a hanger element having a deformed foot at 50 one end thereof penetrating the web of the beam and engaging one of the truss elements, the opposite end of the hanger element comprising a stirrup with a horizontal bottom portion and two spaced apart vertical portions, the exposed portion of the reinforcement 55 in the precast slab resting upon the horizontal portion of the stirrup and supported through the instrumentality of the vertical portions of the stirrup on each side 60 of the reinforcement.

2. The combination with a fabricated beam having a lower longitudinal truss element and an open web, a precast slab of plastic material below the truss element, said 65 slab having a reinforcement therein, a por-

tion of which is exposed, a hanger element having a deformed foot at one end thereof penetrating the web of the beam and engaging the truss element, the opposite end of the hanger element including a stirrup, the exposed portion of the slab reinforcement resting in the stirrup. 70

In testimony whereof, we have hereunto subscribed our names this 2nd day of July, 1929. 75
